UNITED STATES PATENT OFFICE.

FRITHIOF GUSTAF ERICSON, OF TORONTO, ONTARIO, CANADA, ASSIGNOR TO CANADIAN AEROPLANES LIMITED, OF TORONTO, ONTARIO, CANADA, A CORPORATION OF CANADA.

AEROPLANE CONSTRUCTION.

1,247,802.

Specification of Letters Patent. Patented Nov. 27, 1917.

Application filed May 31, 1917. Serial No. 172,034.

To all whom it may concern:

Be it known that I, FRITHIOF GUSTAF ERICSON, of the city of Toronto, in the county of York, in the Province of Ontario, Canada, have invented certain new and useful Improvements in Aeroplane Construction, of which the following is the specification.

My invention relates to improvements in aeroplane construction, and the object of the invention is to devise a form of bar for the ends and back of the plane, which will not only be strong and durable, but also enable the web and the fabric to be secured thereto without any liability of the bar rusting due to the treatment of the fabric, or other causes, and dispense with a tubular bar which splits.

My invention consists of a bar V-shape in cross section, the V form being disposed horizontally, webs with upper and lower ribs, the ends of which embrace the outside of the V bar at the top and bottom, and a securing strap passing around the bar and ribs of the web to which it is suitably secured, the parts being otherwise constructed and arranged in detail as hereinafter more particularly explained.

Figure 1, is a perspective view showing a portion of the bars and webs to exhibit my invention.

Fig. 2, is a perspective detail showing portion of the bar.

In the drawings like letters of reference indicate corresponding parts in each figure.

1 is the longitudinal bar, which forms the back and end bar of the aeroplane, and which is V-shape in cross section. 2 are the webs, which are formed of a central portion 2* and top and bottom ribs 3 tapered toward the end and extending to the top and the bottom of the V-shape bar, which it will be seen is horizontally disposed.

4 is a metal strap, which is suitably secured to the top and bottom ribs 3 and ex-

tends around the bar 1 at the outside as indicated.

The bar 1 is made of steel and is copper plated in order to prevent fabric when it is treated from affecting or rusting the steel 50 as the copper plating both extends to the inside and outside of the bar.

Heretofore it has been the common practice to use tubular bars, which although they are copper plated on the outside will rust 55 on the inside and thereby deteriorate, and, therefore, be a dangerous element in a plane, in which it is so essential that every element should preserve its strength.

Again the difficulty in bending the tube 60 was also very great, but by the construction of my bar the bending is very much more easily facilitated, and the bar is formed without cracking either when bending into flattened form or when bending the bar in 65 a horizontal plane to form an angle.

I wish also to draw attention to the peculiar inturn 1' of the bar at the inner end or open mouth of the bar. Should the fabric of the plane sag, as it frequently does, this 70 inturned end prevents any liability of the bar cutting or otherwise injuriously affecting the fabric.

What I claim as my invention is.

1. In an aeroplane, a bar V-shape in cross 75 section and having the V disposed horizontally with the open end of the V to the inside, the edges of the bar being curved inwardly toward each other.

2. In an aeroplane, the combination with 80 the bar V shape in cross section and disposed horizontally with the open end of the V to the inside, of a web having the upper and lower ribs tapered off to and fitting the upper and lower portions of the 85 bar, and an encompassing strap suitably held on the ribs and extending around the front of the bar.

FRITHIOF GUSTAF ERICSON.
